DESIGN FOR A HAIR DRIER HOOD SHIELD

Helen S. Maulsby, New York, N. Y.

Application September 29, 1939, Serial No. 87,438

Term of patent 14 years

To all whom it may concern:

Be it known that I, Helen S. Maulsby, a citizen of the United States, residing at New York, in the county of New York and State of New York, have invented a new, original, and ornamental Design for a Hair Drier Hood Shield, of which the following is a specification, reference being made to the accompanying drawing, forming part thereof.

I claim:

The ornamental design for a hair drier hood shield, as shown.

HELEN S. MAULSBY.
